UNITED STATES PATENT OFFICE

SIDNEY B. BLAISDELL, OF PHILADELPHIA, PENNSYLVANIA, ASSIGNOR TO FIDELITY
MACHINE COMPANY, OF WILMINGTON, DELAWARE, A CORPORATION OF DELAWARE

BRAIDED PACKING AND PROCESS OF MAKING THE SAME

Application filed October 25, 1928. Serial No. 314,980.

This invention relates to an improved form of braided packing, and the like, and to a special process by which the product is manufactured. The invention relates particularly to the variety of braided packing, which, 5 prior to my invention, was produced by forming a plurality of layers successively one upon another, until a packing of the desired weight and cross-sectional dimensions was obtained.

This method of manufacture was necessarily slow, for the reason that the formation of each superposed layer required the passing of the product through a separate braiding operation. Packing produced in this manner has certain objectionable features, for example, when the threads, of which the layers are composed, begin to wear portions thereof become loose and quite frequently lodge in the valves and between other relatively movable parts of the machinery in which the packing is used. Also in this layer-built packing the separate superposed layers are cemented together with a rubber cement which is objectionable when the packing is used at high temperatures.

The principal object of my invention is to produce a braided packing of any desired weight, in a single braiding operation, which in external appearance greatly resembles the above described layer-built packing, but which is formed in such a manner that all the threads of which the packing is composed interlock within the center of the packing, thus producing a superior article in considerably less time than has been possible heretofore, and obviating the above mentioned objectionable features of the layer-built packing.

In forming my improved interbraided packing I employ a plurality of series of threads, each series being composed of a plurality of individual threads. Each series of threads constitutes a segmental section of the complete packing, in the cross-section of the packing, throughout the length of the packing, and the threads of each series or segmental section are interbraided on the outer surface of the packing with the threads of the series or segmental section lying immediately adjacent thereto, thus the several seg-

mental sections overlap the sections immediately adjacent thereto, and all the threads of all the series are interbraided and thereby interlocked with each other within the center of the packing. Thus a compact braided packing of any desired weight is produced, the number of threads per series and their respective weights, and the number of series employed determining the ultimate weight and cross-sectional dimensions of the packing.

The weight, cross-sectional dimensions, and the cross-sectional configuration of the packing may be further modified to any desired extent by introducing at certain places within, and running longitudinally of, the packing any desired number of core threads around which the threads of the several series are braided. In this manner the packing may be caused to assume a round, square, 70 rectangular, triangular or polygonal form in cross-section, depending upon the number, disposition and relative weights of the respective core threads.

The construction and method of manufacture of the packing forming the subject of my present invention will be fully disclosed in detail, reference being had to the accompanying drawings, of which:

Fig. 1 is an elevation, looking in the direction of the arrow Z, Fig. 2, of a piece of packing made in accordance with the principles of my invention, with a portion cut away to show one thread of each of the series and the manner in which these threads of the several series are braided or interlaced with each other within the center of the packing;

Fig. 2 is a diagrammatic cross-sectional view taken on the line 2-2, Fig. 1, showing the packing in a somewhat expanded state, to illustrate clearly the manner in which the threads of each series or segmental section are braided together on the outside side surface of the packing and how all the threads of all the series are interbraided within the center of the packing;

Fig. 3 is a diagrammatic view somewhat similar to Fig. 2, showing the method of braiding employed, and how the threads of

100

the several series are interbraided to form the complete packing;

Figs. 4 to 7 inclusive illustrate the paths traveled by the respective threads of the respective series during the braiding operation;

Fig. 8 is a cross-sectional view of a piece of packing into which longitudinal core threads have been introduced to increase the weight and cross-sectional dimensions of the packing and to give the packing a substantially square cross-sectional form.

The form of the invention illustrated in the drawing comprises four series of threads A, B, C and D, respectively.

Each series comprises, in the present instance, nine individual threads illustrated at a^1 to a^9 inclusive, b^1 to b^9 inclusive, c^1 to c^9 inclusive, and d^1 to d^9 inclusive.

The threads are individually carried by individual bobbin carriers of conventional form over the bobbin carrier supporting platform of a conventional form of braiding machine, the bobbin carriers for the respective series of threads A, B, C and D moving in the paths and in the directions illustrated in Figs. 4, 5, 6 and 7 respectively, causing the threads of series A to be braided with the threads of the adjacent series B and adjacent series D on the outer surface of the packing; the threads of series B to be braided with the threads of adjacent series A and adjacent series C on the outer surface of the packing; the threads of series C to be braided with the threads of adjacent series B and adjacent series D on the outer surface of the packing; and the threads of series D to be braided with the threads of adjacent series C and adjacent series A on the outer surface of the packing, as illustrated clearly in Figs. 2 and 3 of the drawings.

As shown clearly in Fig. 2 series A and series B interlock on the outer face of the packing in the manner indicated at A—B; series B and C as illustrated at B—C; series C and D as illustrated at C—D; and series D and A as illustrated at D—A.

The path of travel of the threads of series A carries these threads into the interior of the packing and beyond and around the axial center X of the packing; series C which is located diametrically opposite to series A also travels into the interior of the packing and beyond and around the axial center X passing through and interlocking with series A about the center X as clearly shown in Figs. 1 and 2. Series B and series D like series A and C are disposed diametrically opposite to each other at right angles to series A and C, passing through each other about the center X in the same manner as series A and C and also passing through both of the said latter series A and C about the center X as illustrated. In this manner all the threads of all the series are interbraided with

each other and intertwine with each other about the center X, forming a compact mass of intertwining threads within the center of the packing, assuming actual closely contacting positions such as shown by the broken out portion of Fig. 1 of the drawing.

As indicated in the several figures of the drawing the paths traveled by alternate series during the braiding operation are in opposite directions, as shown by the arrows in Figs. 3 to 7 inclusive, thus the threads of series A and C follow what may be termed right hand irregular helical paths longitudinally of the packing, while the threads of series B and D follow left hand irregular helical paths longitudinally of the packing.

The number of threads per series and the number of series in the packing determine the pitch of the helical paths above noted and also determine the character of the braiding or weaving of the threads.

With nine threads per series and using four series as above noted, the appearance of the outer surface of the packing resembles that of a twill weave, in which each diagonally disposed thread passes over two threads diagonally disposed in an opposite direction and under the next two threads disposed in said opposite direction, as clearly shown in Fig. 1. Obviously a change in the number of threads per series, or in the number of series employed, or both, will produce a different twill, such as over one and under one, or over one and under two, etc. Such changes, however, would be within the scope of the present invention.

The paths followed by the bobbin carriers for which the threads of the several series are drawn consist of a number of arc segments connected end to end to form a continuous line of travel for the threads of each series. These arc segments are swung from definite centers disposed in a predetermined relation to each other on the bobbin carrier supporting platform of the braiding machine, bearing the relationship illustrated in Fig. 3, in which the said centers are respectively indicated at 10 to 25 inclusive, and intermediate the paths of the several series are formed spaces 26 to 30 inclusive.

By running core threads longitudinally through the packing in axial alignment with the centers 10 to 25 and through the spaces 26 to 30 the weight and cross-sectional dimensions of the packing may be greatly increased and a substantially round packing produced.

By eliminating the core threads from certain of the centers and spaces the cross-sectional configuration of the packing may be changed to anything desired, such, for example, the square form illustrated in Fig. 8, in which a core thread E is inserted in the axial space 26, a core thread F at the center 10, a core thread G at the center 13, a core thread

H at the center 16, and a core thread I at the center 19.

It will be noted that the core threads F and H are positioned diametrically opposite to each other and located on a line extending through the axial center X of the packing, which lies within the center space 26, and the threads G and I are also positioned diametrically opposite to each other on a line extending through the axis X, the line on which the core threads F and H are located being disposed at right angles to the line on which the core threads G and I are located, thus describing the outline of a square, and consequently producing a substantially square packing.

By placing core threads at those centers and in those spaces, which having connecting lines drawn through them would describe a triangle, such for instance as the centers 10 and 13 and the space 29, a triangular packing would be produced and so on through the various range of possible forms.

Regardless of the positioning of the core threads each core thread will be tightly bound in place by the braiding threads of the several series as they pass between and around the braiding threads of adjacent series and as they pass into the center of the packing and therein intertwine with the braiding threads of all the series about the axis of the packing.

I claim:

1. A braided packing comprising a plurality of series of threads, each series of threads lying within and forming a definite section of the packing transversely and longitudinally thereof, the threads of each section being interbraided with the threads of adjacent sections, and passing from the exterior to the interior of the packing, wherein the threads of each section intertwine with the threads of each of the other sections.

2. A braided packing comprising a plurality of series of threads, each series of threads lying within and forming a definite section of the packing transversely and longitudinally thereof, the threads of each section being interbraided with the threads of adjacent sections, the said adjacent sections overlapping each other along their longitudinally extending edges and the threads of each section passing from the exterior to the interior of the packing, wherein the threads of each section intertwine with the threads of each of the other sections.

3. A braided packing comprising a plurality of series of threads, each series of threads lying within and forming a definite section of the packing transversely and longitudinally thereof, the threads of each section being interbraided with the threads of adjacent sections on the outer surface of the packing, and passing from the exterior to the interior of the packing, wherein the threads of each

section intertwine with the threads of each of the other sections.

4. A braided packing comprising a plurality of series of threads, the threads of each series being interbraided with those of the adjacent series, passing from the exterior to the interior of the packing wherein the threads of each series intertwine with the threads of the other series, and a core thread extending longitudinally of and within the packing around which the threads pass.

5. A braided packing comprising a plurality of series of threads, each series of threads lying within and forming a definite section of the packing transversely and longitudinally thereof, the threads of each section being interbraided with the threads of adjacent sections, passing from the exterior to the interior of the packing, wherein the threads of each section intertwine with the threads of each of the other sections, and a core thread extending longitudinally of the packing within one of the said sections and bound therein by the said interbraiding of said threads.

6. A braided packing comprising a plurality of series of threads, each series of threads lying within and forming a definite section of the packing transversely and longitudinally thereof, the threads of each section being interbraided with the threads of adjacent sections, passing from the exterior to the interior of the packing, wherein the threads of each section intertwine with the threads of each of the other sections, and a core thread extending longitudinally through the center of the packing and bound therein by the said intertwining of the threads of the several series at the center of the packing.

7. A braided packing comprising a plurality of series of threads, each series of threads lying within and forming a definite section of the packing transversely and longitudinally thereof, the threads of each section being interbraided with the threads of adjacent sections, passing from the exterior to the interior of the packing, wherein the threads of each section intertwine with the threads of each of the other sections, a core thread extending longitudinally through the center of the packing and bound therein by the said intertwining of the threads of the several series at the center of the packing, and core threads extending longitudinally of the packing at points removed from the center of the packing and located within the said sections and bound in the packing by the said interbraiding of the threads of adjacent sections.

8. A braided packing comprising a plurality of series of threads, each series of threads lying within and forming a definite section of the packing transversely and longitudinally thereof, the threads of each section being interbraided with the threads of adjacent

- sections, passing from the exterior to the interior of the packing, wherein the threads of each section intertwine with the threads of each of the other sections, a core thread extending longitudinally through the center of the packing and bound therein by the said intertwining of the threads of the several series at the center of the packing, and additional core threads extending longitudinally 10 of the packing at points removed from the said center of the packing being located within the said sections and bound in the packing by the said interbraiding of the threads of adjacent sections.
- 15 9. A process for manufacturing braided packing which is composed of a plurality of threads divided into groups, each group lying within a particular section of the packing as viewed on a plane extending transversely 20 of the packing, the threads of which each section is composed extending from the exterior to the interior of the packing, said process consisting of interbraiding the threads of adjacent sections along the longitudinally extending adjoining edges of the said sections on the outside surface of the packing, intertwining the threads of each section with the threads of each of the other sections within the interior of the packing, running a core thread longitudinally through the packing at the point where the threads of all the sections intertwine with each other, running additional core threads through predetermined 25 points removed from the first said core thread, and braiding the threads of adjacent sections around said core threads respectively.
- 30 10. A process for manufacturing braided packing which is composed of a plurality of threads divided into groups, each group lying within a particular section of the packing as viewed on a plane extending transversely 35 of the packing, the threads of which each section is composed extending from the exterior to the interior of the packing, said process consisting of interbraiding the threads of adjacent sections along the longitudinally extending adjoining edges of the said sections on the outside surface of the packing, intertwining the threads of each section with the threads of each of the other sections within the interior of the packing, 40 running a core thread longitudinally through the packing at the point where the threads of all the series intertwine with each other, and braiding the said intertwining threads around said core thread.
- 45 11. A process for manufacturing braided packing which is composed of a plurality of threads divided into groups, each group lying within a particular section of the packing as viewed on a plane extending transversely 50 of the packing, the threads of which each section is composed extending from the exterior to the interior of the packing, said process consisting of interbraiding the threads of adjacent sections along the longitudinally extending adjoining edges of the said sections on the outside surface of the packing, intertwining the threads of each section with the threads of each of the other sections within the interior of the packing, running core threads longitudinally through pre- 55
- determined sections of the packing, and braiding the threads of adjacent sections around said core threads.
- 60 12. A process for manufacturing braided packing which is composed of a plurality of threads divided into groups, each group lying within a particular section of the packing as viewed on a plane extending transversely of the packing, the threads of which each section is composed extending from the exterior to the interior of the packing, said process consisting of interbraiding the threads of adjacent sections along the longitudinally extending adjoining edges of the said sections on the outside surface of the packing, intertwining the threads of each section with the threads of each of the other sections within the interior of the packing, running a core thread longitudinally through the packing at the point where the threads of all the sections intertwine with each other, running additional core threads through predetermined points removed from the first said core thread, and braiding the threads of adjacent sections around said core threads respectively.
